UNITED STATES PATENT OFFICE.

FRANK HOLTON, OF CHICAGO, ILLINOIS, ASSIGNOR TO FRANK HOLTON & CO., OF CHICAGO, ILLINOIS, A CORPORATION OF ILLINOIS.

MACHINE FOR GRINDING TROMBONE-SLIDES.

1,076,284.

Specification of Letters Patent.

Patented Oct. 21, 1913.

Application filed February 13, 1912. Serial No. 677,278.

To all whom it may concern:

Be it known that I, FRANK HOLTON, a citizen of the United States, residing at Chicago, in the county of Cook and State of Illinois, have invented certain new and useful Improvements in Machines for Grinding Trombone-Slides, of which the following is a specification.

In the manufacture of trombones, the portions of the members which are telescoped to form the slide are constructed so that there will be a snug fit and in order to permit freedom of movement of the slide in the finished instrument, the telescoping portions must be ground while a close fit of the parts must be maintained.

It is one of the objects of the present invention to provide an improved, simple and efficient machine of this class whereby this grinding may be effectively accomplished, while at the same time a proper joint will be maintained.

A further object is to provide an improved machine of this class having means whereby a plurality of slides may be simultaneously ground.

To the attainment of these ends and the accomplishment of other new and useful objects as will appear the invention consists in the features of novelty in substantially the construction, combination and arrangement of the several parts hereinafter more fully described and claimed and shown in the accompanying drawings exemplifying this invention and in which:

Figure 1 is a front elevation of an improved machine of this class constructed in accordance with the principles of this invention. Fig. 2 is a side elevation of the parts shown in Fig. 1. Fig. 3 is a perspective view of a detail. Fig. 4 is a sectional view taken on line 4—4 Fig. 1. Fig. 5 is a detailed sectional view taken on line 5—5 Fig. 2.

Referring more particularly to the drawings and in the present exemplification of this invention, the numeral 10 designates a support, preferably in the form of uprights, upon which the parts are mounted and these uprights may be of any desired height. Secured to the uprights which are preferably spaced and extending across the space between the uprights is a supporting member 11 which is arranged in any convenient posi-

tion for the operator. Secured to this member 11 are any suitable number of clamps each for holding one of the telescoping members of the instrument. Any number of these clamps may be provided, and in the present form of the invention three are shown. As the specific construction and operation of each of these clamps is the same, a specific description of one will apply equally as well to them all.

The clamp comprises spaced jaws 12—13, the jaw 12 constituting the main portion of the clamp and is preferably provided with a base and an upright portion 14 extending above the base adjacent one edge of the base, and projecting beyond the upright and the base is an extension 15 preferably in the form of a trunnion which is pivotally engaged with the member 11 preferably by entering a suitable journal in the member. This trunnion 15 serves as a support for the rear of the clamp and the front thereof is supported in any suitable manner, preferably by means of a link 16 which is pivotally connected as at 17 with the front edge of the base 12 of the clamp and also by a connection as at 18 with a bracket 19, which latter is also secured to the member 11 by suitable fastening devices 20. The member 19 is arranged below and spaced from the base 12 of the clamp so that the clamp will have free pivotal movement with respect to member 11 and the link 16. One edge of the other member 13 of the clamp engages and rests upon the upright 14 and is secured to the upright in any suitable manner, preferably by means of fastening devices 21. The members 12—13 of the clamp are also connected by suitable adjustable fastening devices 22 preferably in the form of screws which pass loosely through the member 13 and have threaded engagement with the base member 12. A stop screw 23 is also provided for limiting the extent of adjustment of the member 13 with respect to the base member 12 and this stop screw 23 passes through and has threaded engagement with the member 13 while its extremity engages and rests upon the adjacent face of the base member 12. Obviously the member 13 is connected loosely with the upright 14 by means of the fastening devices 21 so as to permit of a limited adjustment of the member 13 with respect to the base member 12,

and the stop member 23 is provided for preventing injury to the crossbar 24 of the slide proper 25 of the trombone. The members 12-13 are adjusted so that they will be spaced from each other a sufficient distance to receive and frictionally engage the crossbar 24 of the trombone slide and when the members are once adjusted they will be maintained in this adjusted position so that one slide may be removed and another placed in position. The clamp thus formed is of a width to extend into the space between the sides of the slide member as shown more clearly in Fig. 1, and are of a width less than the space so that when the slide 25 is in position, as shown in Fig. 1, any irregularity or rocking movement which might be caused by the operation of the machine, will be permitted inasmuch as the clamp 20 will rock about its point of pivotal support and the sides of the slide of the instrument will not strike the bracket 19.

In order to prevent the mutilation of marring of the crossbar 24 any suitable material 25 26 such as leather, felt or the like may be provided which is secured to the adjacent faces of the members 12-13 of the clamp. When the clamp members have been once adjusted to the proper position all that is necessary for the operator is to grasp the slide member and force the crossbar 24 into the clamp and between the protecting material 26 in which position the slide will be frictionally held.

Secured to the uprights 10 are suitable guides 27 upon which guides a slide designated generally by the reference numeral 28, is adapted to be reciprocated. This slide 28 may be of any desired or suitable configuration and may be of any suitable material 40 and is arranged above the member 11. The slide is provided at its base with a laterally projecting portion 29 which extends over the clamps. This laterally projecting portion 29 is preferably continuous and is formed in its front edge with cut out portions or recesses 30, the latter being shaped to conform to the configuration of the joints 31 of the instrument (see particularly Fig. 50 1) and is of a thickness to receive the joint. This laterally projecting portion 29 constitutes one of the members of a series of clamps similar to the clamp which is secured to the member 11. The recesses 30 are so arranged that one will be disposed on each side of the fixed clamp which is secured to the member 11 so that when the telescoping members of the instrument are placed in position in the machine, as shown in Fig. 1, 55 the joints 31 will enter the respective recesses 30 and the crossbar 32 will extend across the portion 33 intermediate two of the recesses 30 and which portion 33 forms the lower jaw of the reciprocating clamp. 60 An upright portion 34 is provided on the

laterally projecting portion 39 and is spaced from the body of the slide 28 and corresponds with the upright 14 of the base member 12. One edge of the upper member 35 of the reciprocating clamp engages and rests upon the upright 34 and is connected to the upright by suitable fastening devices 36. Screws 37, similar to the screws 22 of the lower clamp are provided which extend loosely through the member 35 and have threaded engagement with the portion 29 and a stop screw 38 similar to the stop screw 23 is provided for limiting the extent of adjustment of the member 35 with respect to the portion 33. Protecting material 39, similar to the material 26 is provided on the jaws of the clamp thus formed for the preventing mutilation or marring of the crossbar 32. If desired the front edges of the member 35 may be beveled or cut away 85 as at 40 so that the side members 41 of the instrument which are connected by the crossbar 32 will not be damaged when the instrument is being inserted or removed from the machine.

The slide 28, together with the reciprocating clamp or clamps supported thereby is adapted to be reciprocated upon the guides 27 in any desired or suitable manner. In the present exemplification, however, 90 there is shown a driving pulley 42, the shaft 43 of which is journaled in the suitable bearing 44 preferably arranged overhead and to this shaft 43 is connected a crank arm 45. A pitman rod or link 46 is pivotally connected as at 47 with the slide 28 and has an adjustable connection with the crank arm 45 by means of which latter the extent of reciprocating movement of the slide 28 may be varied. In order to effect an adjustment 100 of the pitman rod or link 46 with the crank arm 45, the latter is preferably provided with a groove or channel 48 in which is arranged a slide 49 and a fastening device 50 is provided which passes loosely through 105 the pitman or link 46, the slide 49 and is threaded into an aperture 51 in the bottom of the groove or channel of the crank arm. Any number of these apertures 51 may be provided and it is obvious that they 110 constitute a means whereby a variable stroke of the slide 28 may be provided.

It is thought that the operation of this improved machine will be clearly understood from the above description, but briefly 115 stated it is as follows: During the manufacture of the instrument, the slide members are constructed with a very close fit and which fit would not permit a free and easy movement in the finished instrument. 120 When thus constructed the slide members are placed in the machine by forcing the crossbar 24 of the slide member proper 25 between the members 12-13 of the fixed clamp and by also forcing the crossbar 32 125 130

of the other or telescoping member between the jaws of the reciprocating clamp. After these members have been placed in position, the shaft 43 is then rotated which 5 will impart a reciprocating movement to the slide 28, and the continued reciprocation of the slide 28 will cause the telescoping portions of the members 41 to be reciprocated into and out of the members 10 of the slide proper 25, the latter being held stationary or fixed while the former is being reciprocated. Obviously some abrasive or grinding material in the form of a paste or liquid is applied to the telescoping members when the latter are separated and the 15 constant reciprocation of the parts with respect to each other will cause the abrasive material to correctly and effectively grind the joint. The pivotal movement of the 20 lowermost clamp or the clamp to which the slide proper, in the present form of the invention is connected, will permit the latter to assume a proper position with respect to the other or telescoping member during 25 the grinding operation. After the grinding has been completed the slide 28 is preferably lowered or brought into close proximity to the other clamp so that both of the members may be gripped by the operator 30 and the instrument readily removed from the machine. Obviously the extent of movement of the slide with respect to the fixed clamp is such that during the reciprocating movement of the slide, the telescoping members will not be disconnected 35 with respect to each other.

The parts may be arranged in any convenient position and if desired the instrument may be placed into the machine in an 40 inverted position with respect to the position shown in Fig. 1 and various other changes may be made in the arrangement and operation of the parts without departing from the spirit of this invention.

45 5. What is claimed as new is:—

1. In a machine of the class described, the combination of coöperating holding devices for respectively holding the slides of a wind musical instrument, and means for reciprocating the said holding devices, one of 50 the holding devices being also adapted for pivotal movement during said reciprocation.

2. In a machine of the class described, the combination of coöperating holding devices for respectively holding the slides of a wind musical instrument, and adjustable means for reciprocating the said holding devices, one of the holding devices being also adapted for pivotal movement during 55 said reciprocation.

3. In a machine of the class described, the combination of coöperating clamps for respectively holding the slide members of a wind musical instrument, said clamps being adapted for relative movement, and

means for imparting such relative movement, one of the said clamps being also adapted for pivotal movement.

4. In a machine of the class described, the combination of coöperating clamps for respectively holding the slide members of a wind musical instrument, said clamps being adapted for relative reciprocating movement, and means for imparting such relative movement, one of said clamps being also adapted for another and independent movement during said relative reciprocating movement. 70

5. In a machine of the class described, the combination of coöperating clamps for respectively holding the slide members of a wind musical instrument, said clamps being mounted for relative reciprocating movement, and means for imparting such relative movement, one of said clamps being also mounted for free and independent pivotal movement, and during such relative movement. 75

6. In a machine of the class described, the combination of coöperating holding devices for respectively holding the slide members of a wind musical instrument, said holding devices being mounted for relative reciprocating movement, adjustable means for imparting such relative movement, one of the said holding devices being also mounted for free and independent pivotal movement 90 during such relative movement. 95

7. In a machine of the class described, the combination of coöperating holding devices for respectively holding the slide members of a wind musical instrument, one of said holding devices being fixed and mounted for free swinging movement, the other of said holding devices being mounted for movement toward and away from the last recited holding device, and means for imparting the last recited movement. 100

8. In a machine of the class described, the combination of a support, a holding device fixed for pivotal movement with respect thereto and adapted for holding one of the slide members of a wind musical instrument, a slide mounted upon the support, a holding device connected with the slide for movement therewith and with relation to the other holding device and adapted for holding the other and coöperating slide member of the instrument, and means for imparting reciprocating movement to the slide and the respective holding device said pivoted holding device being free for oscillation during said reciprocating movement. 110

9. A machine of the class described for simultaneously grinding a plurality of coöperating slide members of wind musical instruments, embodying a series of pairs of coöperating holding devices for holding the respective members of the slides, and means for reciprocating the respective holding devices of each pair. 115

10. A machine of the class described for simultaneously grinding a plurality of co-operating slide members of wind musical instruments, embodying a series of pairs of 5 co-operating holding devices for holding the respective members of the slides, and adjustable means for reciprocating the respective holding devices of each pair.
11. A machine of the class described for 10 simultaneously grinding a plurality of co-operating slide members of wind musical instruments, embodying a series of pairs of co-operating holding devices for holding the respective members of the slides, means for 15 reciprocating the respective holding devices of each pair, one holding device of each pair being also mounted for independent swinging movement.
12. In a machine of the class described, 20 the combination of two holding devices for respectively holding in constant engagement the slide members of a wind musical instrument, and means for imparting relative movement to the holding devices, each of 25 said holding devices embodying spaced members, and adjustable fastening devices having engagement with each of the members.
13. In a machine of the class described, 30 the combination of two holding devices for respectively holding in constant engagement the slide members of a wind musical instrument, and means for imparting relative movement to the holding devices, each of 35 said holding devices embodying spaced members, adjustable fastening devices, and
- a stop device for limiting the adjustment of the members.
14. In a machine of the class described, the combination of two holding devices for 40 engaging the respective cross bars of the slide members of a wind musical instrument and holding the slide members in constant engagement, means for imparting relative movement to said devices, said devices embodying spaced members between which the cross bar is gripped and one of said spaced members having open recesses to receive the side members of the respective slide members. 45
15. In a machine of the class described, the combination of two holding devices for engaging the respective cross bars of the slide members of a wind musical instrument and holding the slide members in constant 50 engagement, means for imparting relative movement to said devices, said devices embodying spaced members between which the cross bar is gripped and one of said spaced members having open recesses to receive the side members of the respective slide members, said recesses being shaped to receive and conform to the contour of the adjacent joint portion of the slide member. 55

In testimony whereof I have signed my name to this specification, in the presence of two subscribing witnesses, on this 7th day of February A. D. 1912.

FRANK HOLTON.
